INVENTOR

UNITED STATES PATENT OFFICE.

J. GILBERT JUSTIN, OF SYRACUSE, NEW YORK.

DESIGN FOR AN ATOMIZER.

SPECIFICATION forming part of Design No. 18,975, dated June 12, 1883.

Application filed September 5, 1882. Term of patent 14 years.

To all whom it may concern:

Be it known that I, J. GILBERT JUSTIN, a citizen of the United States, residing at Syracuse, in the county of Onondaga and State of New York, have invented and produced a new and original Design for Atomizers, of which the following is a specification, reference being had to the accompanying photographic illustration thereof, forming a part hereof, which

10 fully illustrates my design.

Heretofore the ordinary construction of atomizers has been to construct the liquid-receiver of a short-bodied large-necked bottle of plain exterior surface, and having a long atomizing-tube projecting above the neck of the bottle and removable to permit of the filling of the receiver with the liquid, the whole presenting to the eye no exterior configuration of surface.

15 20 The leading features of my design are to construct the liquid-receiver of an atomizer of such an exterior configuration of surface as to represent and show the whole or a portion of a human body below the neck suitably draped, and to construct the upper part of the exterior

form and configuration of a human head and neck, within which the atomizing-tubes are inclosed and concealed, and so arranged that the spray is ejected from the mouth, eyes, or other portion of the face, while the air-tube 30 enters the back part of the head of the figure, or at any other point of the figure desired.

The drawing shows the figure of a human being seated cross-legged upon the bottom of an inverted wash-tub as a base or pedestal to 35 support the figure.

I claim—

1. The design for an atomizer-body herein shown and described, consisting of the figure of a human being in exterior configuration. 40

2. The design for an atomizer herein shown and described, consisting of the figure of a human being in exterior configuration mounted upon a base or pedestal.

In witness whereof I have hereunto set my hand this 2d day of September, 1882.

J. GILBERT JUSTIN.

In presence of—

C. W. SMITH,
H. BAXTER.
